UNITED STATES PATENT OFFICE.

CHARLES M. BERDAN, OF MAYWOOD, NEW JERSEY.

BLANKET-HOLDER.

1,156,740.

Specification of Letters Patent.

Patented Oct. 12, 1915.

Application filed January 8, 1915. Serial No. 1,171.

To all whom it may concern:

Be it known that I, CHARLES M. BERDAN, a citizen of the United States, residing at Maywood, in the county of Bergen and State 5 of New Jersey, have invented certain new and useful Improvements in Blanket-Holders; and I do hereby declare the following to be a full, clear, and exact description of the invention, such as will enable others 10 skilled in the art to which it appertains to make and use the same.

This invention has for its object to provide a simple and efficient holder especially designed for reliably holding a blanket or 15 other bed clothes in position over an infant or child.

Another object of the invention is the provision of a holder including an adjustable band adapted to be positioned about the 20 mattress and over the bed clothes and carrying adjustable fasteners or clips whereby the bed clothes may be secured thereto.

With these and other objects in view, the invention consists in the novel construction, 25 arrangement and formation of parts as will be hereinafter specifically described, claimed and illustrated in the accompanying drawing, in which:

Figure 1 represents a plan view of the 30 holder, partly broken away. Fig. 2 represents a longitudinal sectional view therethrough, partly broken away. Fig. 3 represents a sectional view on the line 3—3 of Fig. 1, and Fig. 4 represents a perspective 35 view of one of the adjusting devices removed.

Referring to the drawing in detail, wherein similar reference numerals designate corresponding parts throughout the several 40 views, the numeral 5 indicates a strip of elastic material having metallic reinforcing members 6 secured over the free ends thereof to prevent the fabric from fraying and acting as a stop to prevent the free ends of 45 the strip from becoming disengaged from the attaching plate. The end portions of the strips 5 are doubled back upon each other and wire loops 7 and 8 are movably engaged in the bight of the double ends of said strip. 50 The wire loop 8 is suitably bent to provide a hook adapted to engage the loop 7 to secure the adjacent portions of the strip 5 together.

An attaching plate 9 is formed adjacent

its ends with transverse openings 10 through 55 which each doubled end portion of the strip 5 is threaded. A pair of parallel ears 11 are formed integral with the plate 9 and are apertured to receive the extensions 12 formed integral with an angular clamping lever 13 60 having a handle 14 at one end and a plurality of angularly directed teeth 15 at the opposite or short end adapted to engage and clamp the doubled end portion of the strip 5 against the plate 9 to secure said strip in 65 adjusted position.

One side of each attaching plate 9 is formed with a pair of parallel ears 16 having apertures therein receiving the end portions of a spring wire member 17, the medial portion 70 of which latter is substantially U-shaped. The free ends of the wire member 17 are offset so as to space them from the adjacent edge of the attaching plate 9 and a strap 18 is engaged over said offset ends. The opposite extremity of each strap 18 is threaded through apertures 19 formed in a disk 20. The straps 18 are stitched transversely above the disks 20 and below the offset ends of the members 17. The shank 21 of a button 22 is 80 secured in each of the disks 20.

In use, the band 5 is engaged about a mattress and the loops 7 and 8 are so adjusted, after loosening the doubled ends of the strip 5 by the levers 13 that when engaged the 85 strip or band snugly fits about the mattress. After this adjustment is made the doubled ends of the strip 5 are securely clamped in adjusted position by means of the levers 13 and the bed clothes to be held in position 90 about the child are engaged over the buttons 22 and are securely held thereon by engaging the wire members 17 thereover.

What I claim is:

A blanket holder including a strip of elastic material having the end portions doubled, an attaching plate adjustably positioned on said doubled ends, means for securing the doubled end portions to the attaching plate, 95 blanket securing means carried by the attaching plate, and means for securing the doubled end portions together. 100

In testimony whereof I affix my signature in presence of two witnesses.

CHARLES M. BERDAN.

Witnesses:

CHARLES H. PLENTY,
WALTER I. SCOTT.
